United States Patent Office

Des. 183,271
Patented July 22, 1958

183,271

BOOK REST

Robert Schuttler, Park Ridge, and James V. Gangi, Chicago, Ill., assignors to Bible Holder Mfg. Co., Inc., Chicago, Ill., a corporation of Illinois

Application November 8, 1957, Serial No. 48,380

Term of patent 14 years

(Cl. D33—3)

FIG. 1

FIG. 2

FIG. 3

FIG. 4

Fig. 1 is a side elevational view of a book rest embodying our new design;

Fig. 2 is a front elevational view of the same;

Fig. 3 is a top plan view thereof;

Fig. 4 is a rear elevational view of the same.

The side not shown in Figure 1 is like the side shown.

We claim:

The ornamental design for a book rest, substantially as shown and described.
